UNITED STATES PATENT OFFICE.

FERNANDO C. MARZO, OF PLACENTIA, CALIFORNIA.

CONTINUOUS EVAPORATOR FOR VEGETABLE AND FRUIT PULPS.

Application filed April 30, 1919. Serial No. 293,664.

To all whom it may concern:

Be it known that I, FERNANDO C. MARZO, a citizen of the United States, residing at Placentia, in the county of Orange and State of California, have invented a new and useful Continuous Evaporator for Vegetable and Fruit Pulps, of which the following is a specification.

My invention relates to apparatus for reducing fruit and vegetable pulp, and it consists in the provision of the new and useful features and the improved construction, combination and arrangement of parts, the purpose of which will be apparent to those skilled in the art, from a consideration of the preferred form of construction shown herein.

The invention is more particularly intended for use in reducing to a stiff pulp, cooked fruit or vegetable liquid commonly known to the art as purée, the same being more highly fluid than the pulp to which it is desired it shall be reduced. It is customary to reduce this thickened substance to a predetermined degree of consistency adapted for subsequent use in making tomato paste and ketchup. The invention may also be used for concentrating fruit juices to a predetermined consistency.

30 The principal object of this invention is to provide an evaporator of this character that will occupy a small space relative to the work it will accomplish.

Another object of the invention is to provide an evaporator in which a positive yet simple control of both the heat and the purée or pulp is provided, whereby the desired evaporation is easily and accurately accomplished.

40 Another object is to provide an evaporator of simple construction which will be durable and effective in operation; and which will be capable of handling large quantities of pulp.

45 A feature of the invention is that the evaporator is entirely automatic, except in the opening and closing of valves; consequently eliminating all arduous labor.

Other objects, advantages and features of 50 invention may appear from the accompanying drawing, the subjoined detail description and the appended claims.

The drawing illustrates the invention.

The figure is a central longitudinal section

through the evaporator showing a detailed 55 construction thereof.

In detail, the cylinder 1 is mounted on the frames 2 and 3, the ends of the cylinder being closed by the plates 4 and 5 which are positioned on the inside of the cylinder 60 where they are secured to the ring angle irons 6 and 7 by any well known means.

The exterior surface of the plates 4 and 5 are reinforced by the ribbed bearing plates 8 and 9 secured to the plates by well known 65 means.

Through the plates 4 and 5 and the bearing plates 8 and 9 are the central openings 10 and 11 which form bearings for the hollow shafts 12 and 13. In the openings 10 70 and 11 are the packings 14 and 15, secured in place by the packing rings 16 and 17, said packing rings being secured to the plates 8 and 9 by means of the stud bolts 18. The packing is intended to prevent the escape of steam around the shafts 10 and 11 75 from the cylinder 1.

The inner ends of the hollow shafts 10 and 11 have integral therewith the concave heads 19 and 20 to which are secured by any 80 common means the ring angle irons 21 and 22. The concave heads 19 and 20 are reinforced by the ribbed plates 23 and 24; and to these heads and also to the ring angle irons 21 and 22 is secured the inner cylinder 25. 85

Within the hollow shaft 13 are secured the spiders 26 which have a central opening therethrough large enough for a loose mounting of the feed pipe 27 which preferably has its discharge end turned downward. 90

The other end of the pipe 27 is turned upward and connected to a receptacle 28 and to conduct liquid fruit or vegetable pulp from said receptacle to the evaporating 95 appliance. Near to the intake of said pipe is the hand valve 29.

The receptacle 28 is supplied with pulp from a source not shown, through the pipe 30; and within the receptacle 28 is a float 100 31 which has on its upper side the stem 32; which stem is pointed like a cone valve and performs the function thereof by entering the end of the pipe 30 and shutting off the supply of pulp when the receptacle 28 has 105 been filled sufficiently to raise the float to a position which would close the pipe 30.

From the foregoing it may be seen that

with the receptacle 28 filled with pulp such material will pass the valve 29 and may be discharged through the pipe 27 into the cylinder 25; and that by means of the valve 29 any desired amount of the pulp may be passed to the cylinder 25 in a continuous stream.

The hollow shaft 13 has secured thereon the sprocket wheel 33; which wheel may be driven by any well known means to rotate the cylinder 25 at high speed so that the pulp entering therein through the means just described will flatten out by centrifugal force over the inner surface of the cylinder 15 and at the same time move toward the other end thereof; and as the pulp flattens out and travels along the inner surface of the cylinder 25 it is heated to evaporate a portion of the moisture therefrom.

20 The cylinder 25 is heated by super-heated steam supplied to the cylinder 1 through the pipe 34 which pipe is connected with a boiler, not shown, and within said pipe is the valve 35 by which the steam flow to the cylinder 1 may be regulated; and the steam discharges from the cylinder 1 through the pipe 36.

The cylinder 1 is provided with the thermometer 37 and gage 38 by which indicators 30 the operator can know exactly what temperature and steam pressure is in the cylinder. There is also provided the safety valve 39 by which means the cylinder is made safe against explosion.

35 At the discharge end of the cylinder 25 there is provided the scraper 40 which contacts with the inner surface of the cylinder 25 and removes therefrom the pulp which is conveyed thereto after being subject to drying heat on the inner surface of the cylinder from the intake to the discharge end thereof.

In order to insure a uniform movement of the pulp over the inner surface of the cylinder 25 and thereby insure a requisite and satisfactory evaporation of the moisture therefrom, the inside of the cylinder is provided with the helix 41; which is a metallic ribbon one edge of which is integral 45 with the inside wall of said cylinder, and which is wide enough to prevent the pulp from climbing over the inner edge thereof causing the pulp to travel along the entire 50 length of the channel formed by said helix, from inlet 27 to scraper 40.

55 From the foregoing it will be seen that the pulp will travel a considerable distance in passing along the above mentioned channel; and will thereby be subjected to a pre-determined application of heat that will insure such evaporation of the moisture therefrom, as may be requisite to produce a pulp of the desired stiffness. As the pulp advances it increases in density and finally becomes 60 pasty.

The centrifugal force holds the flowing material against the inner peripheral wall of the cylinder 25 and the heat, the temperature of the fluid material introduced into the receptacle 28 of the cylinder, and the velocity of the air through the cylinder will be adjusted so as to practically reduce the flowing material to a predetermined consistency by the time it reaches the scraper 40, which intercepts the pulp and causes it to flow down through the pipe 41 to the place of packing or storage.

When the rotation of the cylinder is stopped before the pulp supply is shut off and which often happens, due to belt breakage 80 or the stopping of the rotating means, the helix 41 serves to retain any pulp entering the cylinder during such non-rotation thereof at the end nearest its entrance. When the channel nearest the entrance of the pulp becomes 85 full, the pulp will overflow into the next channel, etc. It is therefore seen that when rotation of the cylinder is resumed that the pulp thus entered will only have traversed a slight distance toward the discharge and 90 will still be subjected to travel a considerable distance before reaching the discharge end, and thereby be evaporated to the requisite consistency.

95 After the pulp has passed through the cylinder 25 and has been removed from the surface thereof by the scraper 40, it passes through the discharge pipe 41 to the outer air through the hollow shaft 12.

The hollow shaft is provided with the 100 spiders 42 which have therein a central opening large enough for the discharge pipe 41 to pass through.

The moisture evaporated from the pulp is carried out of the cylinder 25 by means of an 105 air current that is supplied by the fan 43 shown by dotted line in the housing 44; and the fan is operated by the steam rotor 45 in the usual manner.

110 The air passes from the fan through the pipe 46 to the end of the hollow shaft 12 and this shaft and pipe abut end to end so that the air is free to enter the cylinder 25. The passage of the air through the cylinder 25 is indicated by the long arrows and this 115 passage of the air forces the evaporated moisture from the pulp out of the cylinder through the hollow shaft 13.

120 In operation steam is turned into the cylinder 1 by means of the valve 25, and when the thermometer indicates a requisite temperature, power is applied to the sprocket wheel 33 to revolve the cylinder at a speed sufficient to hold by centrifugal force the pulp against the inner surface of the cylinder. 125 Then the valve 29 is opened to permit the liquid supply to flow through the pipe 27 to the cylinder 25; and by means of the two valves 29 and 35 a proper flow of both steam and pulp is easily produced.

With an exceedingly wet pulp a less volume of it will be permitted to pass to the cylinder than in case of pulp requiring but little evaporating; and the volume of pulp passing to the cylinder may be thus regulated by means of the valve 29.

It will be seen that the process is continuous, and that it may be conducted with a minimum amount of labor.

10 The invention admits of modification and changes, and a right is reserved to all such changes as do not depart from the scope and spirit of the invention.

Particular attention is directed to the 15 depth of the channel formed by the helical walls 41. By this means a sufficient body of the liquid pulp will be confined to allow the material to retain a sufficient fluidity as it passes through the apparatus to allow it 20 to flow in a helical course toward the scraper under the centrifugal force. By inspecting the material discharged through pipe 41' the operator can determine whether a greater or less amount of the purée should be fed 25 through pipe 27. If the product is too stiff the purée will be fed more rapidly. If not stiff enough it will be fed more slowly.

I claim:

1. In an evaporator, a steam cylinder; an 30 evaporating cylinder inside of said steam cylinder; means to supply fluid pulp to the inside of the evaporating cylinder at one end thereof; helical means secured to the inside of said evaporating cylinder for passing pulp through said evaporating cylinder, to the other end thereof; a scraper arranged to scrape the product from the cylinder at said other end and a pipe leading from said scraper through the end of the cylinder to 40 discharge the product.

2. In an evaporator, a steam cylinder; an evaporating cylinder inside of said steam cylinder; said evaporating cylinder being provided on its inner peripheral wall with a 45 helical channel of considerable depth extending from one end of said cylinder toward the other end; means for revolving said evaporating cylinder; means for supplying a regulated flow of liquid pulp to one 50 end of said channel; a scraper at the other end of the channel arranged to scrape the material from the wall of the evaporating cylinder at the upper side of said cylinder and a pipe leading from said scraper 55 through the end of the cylinder to discharge said material for passing pulp through said evaporating cylinder.

3. In an evaporator, a steam cylinder having plates at the ends thereof; an evaporating cylinder inside of said steam cylinder; hollow shafts in the ends of said evaporating cylinder and mounted in said plates; helical means secured to said evaporating cylinder for passing pulp through said 60 evaporating cylinder to the top of the inte-

rior peripheral wall at one end of said evaporating cylinder; and a scraper arranged to receive the product from said wall and to discharge by gravity through the plate at that end. 70

4. In an evaporator, a steam cylinder having bearing plates in the ends thereof; hollow shafts in said bearing plates; an evaporating cylinder secured to said hollow shafts; means for rotating said evaporating cylinder and shafts; means for supplying a regulated quantity of pulp to the interior of one end of the evaporating cylinder; helical means secured to the inner periphery of the evaporating cylinder for passing pulp 80 through said evaporating cylinder; a scraper inside said cylinder, at the part thereof near the discharge end, to scrape the material from the inside of the peripheral wall at the end of the evaporating cylinder; 85 and a pipe extending down from said scraper and out through the end wall of the cylinders to discharge the product.

5. In an evaporator, a steam cylinder having bearing plates in the ends thereof; hollow shafts in said bearing plates of said cylinder; an evaporating cylinder secured to said hollow shafts; means for rotating said evaporating cylinder and said hollow shafts; a pipe for discharging pulp by gravity into said evaporating cylinder; a scraper at the top of said cylinder near the end thereof; a pipe leading down from said scraper through the bearing plate at one end of the cylinder for discharging the 100 evaporated pulp from said evaporating cylinder; and a helical ribbon for passing said pulp from said discharge pipe to said scraper. 90

6. In an evaporator, a heated cylinder; 105 hollow shafts at the ends of said cylinder; bearings for said shafts; means for rotating said shafts and heated cylinder; a helical ribbon integral with the inside peripheral walls of the heated cylinder for passing pulp 110 through said heated cylinder; and means for scraping the product from the other end of said cylinder and discharging it by gravity through the hollow shaft at such other end. 115

7. In an evaporator, a stationary cylinder; a revolvable cylinder in said stationary cylinder; means for revolving said revolvable cylinder; means for carrying pulp material to said revolvable cylinder; helical means secured to the inner periphery of said revolvable cylinder for causing 120 said material to pass in a helical course around the inside peripheral walls of said revolving cylinder; and means to receive such material from said wall at the further 125 end of the cylinder and to discharge said material through the end of said cylinder.

8. In an evaporator, a stationary cylinder; a revolvable cylinder in said stationary cylinder; a guiding ribbon helically ar- 130

ranged against the peripheral wall in said revolvable cylinder for passing pulp through said cylinder; means for revolving said revolvable cylinder; means for conveying pulp to one end of the channel formed by said helical ribbon inside said revolvable cylinder; and means for collecting the product from the other end of the said channel and discharging the same from said revolvable cylinder.

9. In an evaporator, in combination with a stationary cylinder and means for heating said cylinder; of another cylinder seated revolvably inside of said stationary cylinder; a metallic helix secured to the inner wall of said inner cylinder for passing pulp through said cylinder; means to revolve said inner cylinder; a scraper to scrape the material from the inner wall of said cylinder;

der; and means to supply pulp material to 20 said inner cylinder.

10. In an evaporator, the combination with a stationary cylinder and means for heating said cylinder; of a cylinder revolvable inside said stationary cylinder; helical 25 means for passing pulp along the inner peripheral walls of the revolvable cylinder, and a scraper to scrape pulp from the inside of the peripheral wall at one end of the revolvable cylinder and to discharge by 30 gravity through one end of said revolvable cylinder.

In testimony whereof, I have hereunto set my hand at Los Angeles California, this 22nd day of April, 1919.

FERNANDO C. MARZO.
